UNITED STATES PATENT OFFICE.

HANS C. HANSON, OF ALBERT LEA, MINNESOTA, ASSIGNOR TO AMERICAN GAS MACHINE COMPANY, OF ALBERT LEA, MINNESOTA, A CORPORATION OF MINNESOTA.

SUPPORT FOR FOLDING CAMP STOVES AND OVENS.

Application filed August 3, 1925. Serial No. 47,774.

This invention relates to a folding camp stove and particularly to a collapsible and extensible support adapted to support said stove and an oven used therewith. Said folding camp stoves are now used in very large numbers by tourists and campers and it is quite desirable on many occasions to have this stove supported at some distance from the ground or floor, so that it is not necessary to bend over the same to such a great extent. It is often desirable to have an oven in connection with such a stove and when the stove is mounted on said support, means should also be provided for supporting the oven, especially when it is disposed at the rear of the stove casing.

It is an object of this invention therefore, to provide a very simple and efficient collapsible and extensible support for a folding camp stove. It is a further object of the invention to provide such a support which may be collapsed into very small space and be disposed on the casing of the folding camp stove. It is still another object of the invention to provide such a collapsible support having means thereon for supporting an oven which means is also collapsible in close proximity to the collapsed support.

This and other objects and advantages of the invention will be fully set forth in the following description, made in connection with the accompanying drawings in which like reference characters refer to the same parts throughout the different views and in which Figure 1 is a perspective view showing the camp stove and oven supported on the support. Figure 2 is a plan view showing the camp stove casing open and the support in collapsed condition therein, and Figure 3 is a perspective view of the support in collapsed position.

Referring to the drawings a camp stove of the folding type is shown comprising a casing 5 illustrated as of rectangular shape in cross section, said casing having secured therein a manifold 6 comprising a pair of burners 7 to which manifold a vaporizing tube 8 is adapted to be connected, which tube is connected to a fuel supply tank 9. The tank when in operative position is disposed without the casing 5 and is disposed in the casing as shown in Figure 2 when the stove is in collapsible and packed condition. An air pump 10 is also shown disposed in cas-

ing 5, which pump is used to place the fuel in tank 9 under pressure. A grid 11 is hinged at the rear side of casing 5, by means of clips 12 secured to the casing 5, which grid rests at its free edge on a ledge 5^a at the front of the casing. The casing 5 is provided with four legs 5^b adapted to be swung into the case when the stove is in collapsed condition or to be swung out of the case into the supporting position shown in Figure 1, said legs having means thereon (not shown) for holding them in such projected position. The casing 5 is also provided with a handle 5^c by which it may be carried when in collapsed position. The stove described may be substantially like that shown in applicant's prior Patent 1,287,152, granted August 9, 1921. The stove and specifically casing 5 has an oven designated generally as 14 secured thereto, which oven comprises a rectangular plate 13 hinged to the rear top edge of casing 5 by clips 15. The plate 13 has a plate 16 hinged at each end thereof and also has a plate 17 hinged to its rear edge. The plate 17 in turn has a plate 18 hinged thereto at its free longitudinal edge, the plates 13, 16, 17 and 18 being arranged to form an oven as shown in Figure 1. The oven structure 14 forms no part of the present invention but is more fully disclosed and claimed in applicant's co-pending application executed of even date herewith S. N. 49,473.

In accordance with the present invention, a support is provided for the stove which support comprises four legs 20, disposed substantially at the corners of a rectangle and preferably converging slightly toward their upper ends. While the legs 20 may be variously formed, in the embodiment of the invention illustrated, they are shown as formed of angle bars having their angles directed inwardly. The legs 20 at each side of said rectangle are connected by pivoted link structures. The pivoted link structures at the ends of the rectangle comprise a pair of links 21 pivotally connected substantially midway of their ends by the pivots 22. The links 21 are connected at their upper ends to one flange of the legs 20 by the pivot members 23 which are fixed relatively to the legs 20. The links 21 at their lower ends are pivotally connected to the legs 20 by the pivots 24 and the pivots 24 are slidable in

longitudinal slots 20^a formed in one flange of the legs 20. The link structures at the long side of said rectangle comprise links 25 and 26. The links 25 are pivotally connected at one end and the pivot members 25 are pivotally connected to the legs 20 at their other end by the pivot members 28. The links 26 are pivotally connected at one end by the pivot member 29 and are connected to the legs 20 at their other end by the pivots 30, which pivots 30 are slidable in longitudinal slots 20^b formed in the flange of legs 20. The links 26 are disposed oppositely to the links 25 and cross the same substantially midway thereof, said links being connected by the pivot members 31. It will be seen that the links 25 and 26 form the well known lazy tong link structure. Each of the links 20 has secured thereto adjacent its top, a clip 32 formed of a flat piece of material having its upper portion substantially parallel to the side flange of the leg 20 or substantially parallel to the long side of said rectangle, said clip being curved or bent at its bottom to form a substantially horizontal portion 32^a, the lower portion of said clip then engaging the flange of the leg 20 and being secured thereto in any suitable manner as by spot welding or riveting. The legs 20 at the rear end have secured thereto by the pivot members 23 an arm 33, said arm extending along the outer and end side of the leg 20, said pivot 23 being disposed between the ends of the said arm. Each arm 33 has one end bent substantially at right angles to form a small triangular lug 33^a and the other end of said arm is cut on a bevel or at an angle to the length of said arm as shown at 33^b. As shown in Figures 1 and 3, the length of arm 33 between its pivot 23 and the end 33^b, is much greater than its length between pivot 23 and the lug 33^a.

In operation when it is desired to support the stove in operative position, the legs 5^b will be extended or projected as shown in Figure 1 and the legs 20 will be separated and disposed as shown in Figure 1. When the legs are so separated it will be noted that pivot members 24 are at the top of the slots 20^a and pivot members 30 are at the top of the slots 20^b. The lower corners of the legs 5^b are now inserted between the inner side of clip 32 and the flange of leg 20 which is parallel thereto. It will be seen that the leg will be prevented from moving outwardly or toward the end of said rectangle by the other flange of leg 20. A socket or channel is thus provided for the leg substantially closed on three sides. The arms 33 are now swung to the position shown in Figure 1, in which the lug 33^a engages the lower edge of one of the links 21 so that the upper portion of said arms are firmly held in position. The stove casing 5 is now firm-

ly and securely held in and supported by the leg structure or support and the plate 13 may rest on the ends 33^a of rods 33 as shown in Figure 1. The weight of the stove resting on the upper end of the legs 20 owing to the diverging relation of these legs tends to further diverge them so that the pivot members 24 and 30 are pressed upwardly against the upper sides of their respective slots. There is no tendency therefore for the leg structure to collapse and the same is rigidly and securely maintained in its operative position.

When it is desired to collapse the stove structure the same is lifted from the legs 20, the legs 5^b are swung into the casing 5 and the stove placed in collapsed position as set forth in applicant's prior patent, previously identified. The oven 14 is then placed in collapsed position as set forth in applicant's co-pending application above identified. The arms 33 are now swung out of engagement with the legs 21 and said arms swung along side of the legs 20 in parallel relation thereto as shown in Figure 3. The legs 20 are then moved toward each other in transverse directions, the links 21 swinging about their pivots 22 and 23 and the pivot members 24 moving downward in the slots 20^a. The links 25 and 26 also swing about their pivots 27, 28, 29 and 31 and the pivot members 30 move lengthwise in slots 20^b. The legs are thus collapsed into closely adjacent position as shown in Figure 3, the links 21, 25 and 26 being folded into compact relation between the legs 20. The support is now in sufficiently compact position to be placed within the casing 5 as shown in Figure 2. The entire stove is thus brought into very small space and is in compact condition for transportation as illustrated in said co-pending application.

From the above description it is seen that applicant has provided an extremely simple camp stove structure comprising a collapsible and extensible support for holding the stove and the oven used therewith. The parts of the support are very few in number and extremely simple in construction and yet are quite rugged. The support can be almost instantaneously placed in collapsed or extended position and the stove can be easily and quickly supported thereon. The device has been amply demonstrated in actual practice and found to be very successful and efficient.

It will of course be understood that various changes may be made in the form, details, arrangements and proportions of the parts without departing from the scope of applicant's invention which generally stated consists of a device capable of carrying out the objects above set forth and in the novel parts and combination of parts disclosed and defined in the appended claims.

What is claimed is:

1. A camp stove structure having in combination a burner-containing casing, legs for supporting said casing, a collapsible and extensible stand arranged to support said legs when in extended position, an oven having an open bottom disposed at the rear of said casing, and means on said stand for supporting said oven with one side in substantially horizontal position and substantially at the level of the top of said casing with said open bottom substantially vertically disposed, said stand being adapted to be received in said casing when in collapsed condition. 10
2. A support for a camp stove casing having in combination four legs disposed at the corners of a rectangle, a pivoted link structure connecting said legs at each side of said rectangle, said link structures being secured to said legs by a fixed pivot adjacent one end of each leg but connected to said legs by a pivot moving in a slot adjacent to the other end of each leg, whereby said link structures can be collapsed and said legs brought into closely adjacent parallel relation. 25
3. A collapsible and extensible stand adapted to support a folding camp stove and comprising four legs, disposed at the corners of a rectangle, a pair of links pivotally connected at their centers and pivotally connected at their upper ends, respectively, to said legs about fixed axes and extending between the legs at the ends of said rectangle, said legs having slots extending longitudinally thereof adjacent their lower ends, means carried by the lower ends of said links, respectively, slidable in said slots, and links pivotally connected together and pivotally connected to said legs and extending between the same at the sides of said rectangle, whereby said legs and links may be expanded to supporting position or collapsed to substantially parallel positions. 35
4. A collapsible and extensible stand adapted to support a folding camp stove and comprising four legs, disposed at the corners of a rectangle, a pair of links at each end of said rectangle pivotally connected at their centers and pivotally connected to the legs at both their ends, one set of ends of each pair of said links having means movable in slots in said leg and adapted to engage the ends of said slots as stops when said stand is extended, an arm pivoted between the ends to each of the legs at one side of said rectangle adapted to be swung alongside said leg or to be swung with one end extending upwardly and outwardly at one side of said rectangle above the top of said leg and having a laterally bent end adapted to engage one of said links to hold said arm in said latter position to support an oven at one side of said stove, said arm being also adapt- 45
- ed to be swung into position parallel with its respective leg when in collapsed position. 5
5. A collapsible and extensible stand adapted to support a folding camp stove and comprising four legs disposed substantially at the corners of a rectangle and diverging slightly downwardly, a pair of links pivotally connected at their centers disposed at each end of said rectangle, said links being connected by pivots at their upper ends to said legs respectively and having means at their lower ends held in and sliding in slots in said legs, articulated links extending between said legs at the sides of said rectangle, an arm at each end of said rectangle pivoted adjacent one end to one of said legs by the pivot connecting one of said pairs of links to said legs, said arm being adapted to swing with its upper and long end extending away from said link and substantially in alignment with said link, said arm having a stop means at its shorter and lower end adapted to engage said link to hold said arm in extended position, said arm being swingable into position substantially parallel with the leg to which it is connected when said stand is in collapsed position. 60
6. A support for a camp stove casing having in combination four legs disposed at the corners of a rectangle, said legs being formed of angle bars with their angles disposed inwardly, pivoted links connecting said legs at each side of said rectangle, said legs each having a clip secured thereto adjacent its upper end having a substantially horizontal portion adapted to support a leg of said casing and having a portion extending parallel to the flange of said angle bar at the side of said rectangle, adapted to hold said leg from inward lateral movement. 65
7. A collapsible and extensible stand adapted to support a folding camp stove, and comprising four legs disposed at the corners of a rectangle, said legs each having a pair of elongated slots adjacent their lower ends, pairs of links pivotally connected intermediate their ends and having their upper ends pivotally connected to said legs adjacent the upper ends of the latter and about fixed axes, said pairs of links extending respectively between the legs at the ends of said rectangle and having means secured thereto at their lower ends slidable in said slots and said legs, respectively, of two sets of links each comprising two pairs of links pivotally connected intermediate their ends, one link of each pair being pivotally connected at its upper end to one of said legs adjacent the upper end of the latter and about a fixed axis and the other link of each pair having means at its lower end slidable in one of said slots in said legs, the other ends of said links being pivotally connected together, said sets of links extending between said legs at the sides of said rectangle whereby said 100
- 110
- 115
- 120
- 125
- 130

legs and links may be extended to supporting position or collapsed into substantially parallel position.

8. The structure set forth in claim 7, said legs being in the form of angle irons with the sides of said angles substantially parallel to the sides of said rectangle and said links being disposed at the inner sides of said angles.

9. A collapsible and extensible stand adapted to support a folded camp stove and comprising four legs disposed at the corners of a rectangle, a pair of links at each end of said rectangle pivotally connected intermediate their ends and respectively connected to said legs at each end of said rectangle, a plurality of pivotally connected collapsible links

disposed at each side of said rectangle, the ends of said latter links adjacent the ends of said rectangle being pivotally connected respectively to said legs, the connection of all of said links adjacent one end of said legs being about fixed pivots and the connection adjacent the other end of said legs being about pivots slidable longitudinally of said legs, said legs having means at their upper ends for supporting a camp stove, whereby said stand may be collapsed with said legs and links in contact and substantially parallel relation.

In testimony whereof I affix my signature.

HANS C. HANSON.
